J. E. CASSIDY

CUSHIONING SUPPORT

Filed April 12, 1920

Inventor:
James Edward Cassidy
By:
Jones, Addington, Ames & Lebolds Atty's.

UNITED STATES PATENT OFFICE.

JAMES EDWARD CASSIDY, OF WASHINGTON, DISTRICT OF COLUMBIA, ASSIGNOR TO STEVENS PARTITION AND FLOOR DEADENER COMPANY, OF CHICAGO, ILLINOIS, A CORPORATION OF ILLINOIS.

CUSHIONING SUPPORT.

Application filed April 12, 1920. Serial No. 373,181.

To all whom it may concern:

Be it known that I, JAMES EDWARD CASSIDY, a citizen of the United States, residing at Washington, District of Columbia, have invented new and useful Improvements in Cushioning Supports, of which the following is a full, clear, concise, and exact description, reference being had to the accompanying drawing, forming a part of this specification.

My invention relates to sound-deadening means, and it has particular relation to means of the character designated embodying cushion supporting members which are adapted to engage structural sustaining members whereby the sound vibrations generated in one portion of a building are precluded from travelling through a supporting floor or partition into another portion 20 of said building by reason of the continuous physical contact of the structural sustaining members employed.

For a better understanding of my invention reference may be had to the accompanying drawing, in which;

Fig. 1 is an elevational sectional view showing my improved sound-deadening means embodied in a floor structure;

Figs. 2, 3 and 4 are elevational views of modified cushioning means constructed in accordance with my invention, Fig. 2 being an end sectional elevational view through a portion of the structure illustrated in Fig. 1; and,

Fig. 5 is an enlarged perspective view of the manner in which the cushioning means employed in my invention are disposed in one embodiment thereof.

I have discovered that in order to obtain satisfactory sound insulation it is necessary to eliminate all continuous physical contact between sound absorbing mediums. Moreover, while efforts have heretofore been made to obtain a sound insulation through the employment of one cushioning device this does not give satisfactory results. Experiments have proved that, when but one cushioning device is interposed between a portion of a building in which sound vibrations are generated and another portion thereof, from which it is desired to exclude said vibrations, some of the latter will invariably, as expressed in the art, "leak through."

I therefore, so dispose and so embody 55 cushioning supports in my sound-deadening means that a plurality thereof are interposed between the sound-vibration generating medium and that portion of the building from which it is desired to exclude said vibrations. I accomplish this end by a particular construction of the cushioning means, as well as by the manner of placing the same, as will be hereinafter pointed out.

These means are so constructed that a plurality of cushioning members are compactly embodied in one device, and moreover, the cushioning members are so disposed that the device may be interposed between two sound absorbing mediums with a minimum 70 consumption of space and with the greatest simplicity of installation.

Referring now more particularly to the drawings and considering Figs. 1, 4 and 5, a cushioning device 10, comprising two opposed U-shaped members 11 and 12 is shown. The members 11 and 12, in the figures referred to, are secured in back-to-back relation and the arm portions thereof are disposed at right-angles to each other.

Arranged within the U-shaped members 11 and 12 are pads 13 which afford cushion supports for structural-sustaining members, as shown. In Figs. 1 and 2, such members are shown at 14 and 15, the former comprising a stringer to which is secured flooring 16. The stringer 15, on the other hand, is secured between the padded portion 11 of the device 10 and a padded portion 17 of another and differently constituted cushioning device 18, the latter being provided with a supporting means 19 which is in turn secured to a rough flooring 20. It will be observed that the rough flooring is secured in a conventional manner to beams 21.

In Fig. 3, I have illustrated the manner in which two of my improved devices may be interposed between two sound-absorbing mediums. Here the bottom of the stringer 15 is positioned in the same kind of equitant cushioning device as is used at the top thereof. The downwardly extending equitant portion of the lower cushioning device straddles a stringer 22 which is in turn secured to flooring or ceiling 23.

In connection with the embodiment of my invention just described, it will be observed that by using two of the cushioned-members

in the manner shown a very compact sound-deadening construction may be realized.

An even more compact structure is illustrated in Fig. 4 wherein the stringer 15 is secured directly to a ceiling or floor portion 24. It will be observed that the same manner of mounting the equitant portions is illustrated in the enlarged view of the Fig. 5. This, however, is merely illustrative and it is obvious that the equitant portions may be secured in back-to-back relation in such manner that the arm portions thereof are in the same plane. I find, however, that the above illustrated embodiment results in an especially compact and simple sound-deadening construction.

It will be observed from the above description that I have provided a construction in which a plurality of cushioning pads are employed whereby those vibrations, which "leak through" the first sound-insulating cushions, are absorbed, and it will, moreover be observed that by the particular arrangement of the equitant, pad-retaining members, which I have illustrated, I am enabled to interpose the required number of devices between two sound-absorbing mediums with a minimum consumption of space.

While I have illustrated a plurality of embodiments of my invention it is apparent that many modifications therein may occur to those skilled in the art, I desire, therefore, that my invention be limited only by the scope of the prior art or by the statements of the appended claims.

Having thus described my invention, what I claim as new and desire to secure by Letters Patent is:

1. Sound-deadening means comprising a cushioning support embodying opposed

pads adapted to engage floor-supporting members.

2. Sound-deadening means comprising a cushioning support embodying opposed U-shaped pieces having supporting pads adapted to engage floor-sustaining members.

3. Sound-deadening means comprising opposed cushion-supporting members provided with base portions and arms extending therefrom whereby structural sustaining members on opposite sides of said means are afforded padded seats.

4. Sound-deadening means comprising opposed cushion-supporting members adapted for equitant engagement with structural-sustaining members.

5. Sound-deadening means embodying opposed equitant, cushion-supporting members.

6. Sound-deadening means embodying opposed equitant, cushion-supporting members, the arm portions thereof being arranged at right angles to each other.

7. Sound-deadening means embodying opposed equitant members provided with cushion linings, said members being arranged in back-to-back relation to afford padded seats for structural supporting members on opposite sides of said means.

8. Sound-deadening means embodying opposed equitant members provided with cushion linings, said members being arranged in back-to-back relation to afford padded seats for angularly-disposed structural supporting members on opposite sides of said means.

In witness whereof, I have hereunto subscribed my name.

JAMES EDWARD CASSIDY.
